US00D574497S

(12) **United States Design Patent**
Kitamura et al.

(10) **Patent No.:** **US D574,497 S**
(45) **Date of Patent:** **** Aug. 5, 2008**

(54) **SPHYGMOMANOMETER**

(75) Inventors: **Masashi Kitamura**, Matsusaka (JP); **Tadashi Koike**, Kyoto (JP); **Yukiko Mitsunami**, Otsu (JP); **Takahide Tanaka**, Otsu (JP); **Hiroyuki Kato**, Kyoto (JP); **Masayuki Fukutsuka**, Uji (JP); **Takashi Shigeno**, Kawasaki (JP); **Kazuya Andachi**, Kawasaki (JP)

(73) Assignee: **Omron Healthcare Co., Ltd.**, Kyoto-shi, Kyoto (JP)

(**) Term: **14 Years**

(21) Appl. No.: **29/287,652**

(22) Filed: **Sep. 4, 2007**

(57) **CLAIM**

The ornamental design for a sphygmomanometer, as shown and described.

DESCRIPTION

FIG. 1 is a perspective view of another embodiment of a sphygmomanometer showing our new design;

FIG. 2 is front elevational view thereof;

FIG. 3 is a rear elevational view thereof;

FIG. 4 is a top plan view thereof;

FIG. 5 is a bottom plan view thereof;

FIG. 6 is a right side elevational view thereof; and,

FIG. 7 is a left side elevational view thereof.

The broken lines shown in the figures are for illustrative purpose only, and form no part of the claimed design.
